UNITED STATES PATENT OFFICE

JESSE D. LYON, OF CINCINNATI, OHIO

BALL MARKER

Application filed July 15, 1931. Serial No. 550,876.

This invention relates to a ball marker such as may be used in impressing a name or identifying mark upon golf balls or the like.

An object of the invention is to provide a device for the purpose stated which is so constructed as to permit of its being readily and conveniently carried about in one's pocket or in a small substantially flat container.

10 Another object is to provide a device of the above character that is simple and easy to operate, and which may be manufactured at low cost.

15 Another object is to provide a ball marker which is complete in itself, there being a type inker disposed within the handle thereof.

These and other objects are attained by the means described herein and disclosed in the accompanying drawing, in which:

20 Fig. 1 is an elevation view of the device shown in position for marking a ball.

Fig. 2 is a side elevational view taken on line 2—2 of Fig. 1.

25 Fig. 3 is a cross-sectional view taken on line 3—3 of Fig. 1.

Fig. 4 is a view similar to Fig. 1 showing the relationship of parts after the marking operation.

30 Fig. 5 is a cross-sectional view of the type inker forming a detail of the invention.

Fig. 6 is an isometric view of a circular ball support or ring forming a detail of the invention.

35 Fig. 7 is an isometric view of the ball marker frame.

The ball marker of the present invention is one which may be referred to as an individual ball marker, as it is constructed in such manner and proportions that it may conveniently be carried about in a substantially flat condition and may be operated without supporting it on a table or the like.

40 The frame of the device comprises a pair of similar stamped metal oval or nearly circular flat members 9 fixed in spaced parallelism by any suitable means such as rivets or screws 10 entering a separating block 12. The members 9 preferably are shaped so that the opposite end regions are of circular formation and connected by straight parallel wall

portions 13, the parallel wall portions being provided for the purpose of affording a track or guide for a circular or ring shaped ball support 14, which latter may be moved bodily along the major axis of the frame, between 55 the members 9. Such movement is effected by means of a rotatable handle 15 screw threaded as at 16 in blocks 12, which handle is provided with an anti-friction abutment 17 which may be in the form of a hardened steel 60 ball rotatably mounted in the end of the handle. The ball is adapted to ride upon a track 18 on the periphery of the ball support 14 when the actuating handle 19 is moved from the position of Fig. 1, to the position 65 of Fig. 2. At the same time, a die block 20, having extending type 21, rotates on its pivot 22 and impresses the type into the surface of the ball 23, the depth of the impression being determined by the amount of force with 70 which the steel ball 17 contacts the track 18 of the ball support. By screwing up on the handle 15, the impression may be made very deep, while by unscrewing it the ring or ball support 14 may be moved from the die suf- 75 ficiently to permit insertion or removal of a golf ball or the like 23 laterally of the ring.

The ball support 14 comprises a pair of circular ring members 24 each of which has an annular outwardly extending flange 25 80 curved to provide a seat for the ball 23 (Fig. 3). The ring members are held in spaced parallel relationship by reason of their attachment to opposite faces of an arcuate spacer 26, which also forms the track 18. The spacer is of approximately a half circle, wherefore the space or passage 27 thereby left between the ring members 24 opposite the spacer 26, may admit the die block 20 85 as shown in Fig. 3. The actuating handle 19 may be, and preferably is, secured to the spacer 26, and its shape is immaterial to the invention. The abutment of the flanges 24 of the ring members upon the inner faces of 90 the frame members 9, precludes disassociation of the ball support member and the frame 9—9. The flanges 25 of the rings extend outwardly from the openings in the frame members, and they also abut the 100

straight walls 13, relative to which they may slide.

The bore 28 in the handle is adapted to receive an inking device 29 which may consist of a tube having a suitable wick or the like 30 extending from one of its ends, and a knurled head 31 whereby it readily may be grasped for removal from the bore 28. The inking device may be hollow and contain a supply of ink.

The operation of the device is as follows. The handle 15 is first unscrewed sufficiently to admit the ball 23 between its seat on the ball support and the die 20, the actuating handle 19 being disposed in the starting or initial position indicated in Fig. 1. After inking the type, the handle is screwed up sufficiently to move the ball upwardly until the first type on the die sinks into the material 20 of the ball. The actuating lever 19 is then moved through an arc to the end of its stroke (Fig. 4), which effects movement of the ball 23 bodily with the ball support 14 and thereby causes movement of the die about its pivot 25 22 for successively sinking the die characters into the material of the ball. After the ball is marked, it may be removed from the device by unscrewing slightly the handle 15. If the working face of the die is not too long, the die will come to the end of its movement before the actuating lever 19 comes to the end of its movement, whereupon the ball 30 will automatically be ejected. This condition is shown in Fig. 4.

The pivot 22 may be a screw shouldered as shown in Fig. 3 for effecting spacing of the members 9 at their free ends, the screw entering the perforations 35 therein. The cooperative nut 36 may be removed, if desired, and the screw withdrawn for the purpose of releasing the die for replacement purposes. When it is desired to carry the device in one's pocket, or to conveniently arrange it in a small leather or other container, the handle is unscrewed from the bore 36 (Fig. 45 7). The two parts then may be readily placed in a substantially flat handy container.

It is to be understood that various modifications and changes in structural details of the device may be made, within the scope of the claims, without departing from the spirit of the invention.

What is claimed is:

1. In a ball marker of the class described the combination of a light-weight frame provided with a holding handle, whereby the device may be held in one hand, a ball support mounted for movement relative the frame, a movable die for operating upon a ball to be marked, and an actuating lever to be operated by the other hand for moving the ball support and the ball supported thereby while subjected to the die.

2. In a ball marker of the class described

the combination of a light-weight frame provided with a holding handle, whereby the device may be held in one hand, a ball support mounted for movement relative the frame, a movable die for operating upon a ball to be marked, an actuating lever to be operated by the other hand for moving the ball support and the ball supported thereby while subjected to the die, and means for relatively moving the ball and die for varying the depths of impression of the die upon the material of the ball.

3. In a ball marker of the class described the combination of a light-weight frame provided with a holding handle, whereby the device may be held in one hand, a ball support mounted for movement relative the frame, a movable die for operating upon a ball to be marked, an actuating lever to be operated by the other hand for moving the ball support and the ball supported thereby while subjected to the die, and means associated with the holding handle for relatively moving the ball and die for varying the depth of impression of the die upon the material of the ball.

4. In a ball marker of the class described the combination of a light-weight frame provided with a holding handle, whereby the device may be held in one hand, a ball support mounted for movement relative the frame, a movable die for operating upon a ball to be marked, an actuating lever to be operated by the other hand for moving the ball support and the ball supported thereby while subjected to the die, a die inking device supported within the holding handle, and means for relatively moving the ball and die for varying the depth of impression of the die upon the material of the ball.

5. In a ball marker of the class described the combination of a frame comprising spaced parallel ring members having guide portions thereon, a marking die pivotally mounted on the frame, a movable ring-shaped ball support for reception of a ball, flanges on said ball support extending through the oval-shaped ring members for rotatably and reciprocally supporting the ball support upon the frame members, an arcuate track on the ball support, and adjustable means contacting the track and applying force thereto for moving the ball support bodily toward the marking die.

6. In a ball marker of the class described the combination of a frame comprising spaced parallel ring members having guide portions thereon, a marking die pivotally mounted on the frame, a ring-shaped ball support for reception of a ball, flanges on said ball support extending through the oval-shaped ring members for rotatably and reciprocally supporting the ball support upon the frame members, an arcuate track on the ball support, adjustable means contacting the track and

applying force thereto for moving the ball support bodily toward the marking die, and an actuating lever associated with the ball support for manual rotation thereof relative to the supporting frame.

In testimony whereof, I have hereunto subscribed my name this 13th day of July, 1931.
